UNITED STATES PATENT OFFICE

FRANK M. ROGERS, OF SEATTLE, WASHINGTON, ASSIGNOR OF ONE-THIRD TO JOSEPH E. NICHOLSON AND ONE-THIRD TO CODY C. COX, BOTH OF SEATTLE, WASHINGTON.

BURIAL STRUCTURE.

1,096,758.

Specification of Letters Patent.

Patented May 12, 1914.

Application filed February 20, 1912. Serial No. 678,777.

To all whom it may concern:

Be it known that I, FRANK M. ROGERS, a citizen of the United States, and a resident of Seattle, in the county of King and State of Washington, have invented a new and Improved Burial Structure, of which the following is a full, clear, and exact description.

The object of the invention is to provide a new and improved burial structure or building, arranged to permit of holding burial services therein, to provide a receiving vault for temporarily receiving bodies, and to provide thoroughly ventilated crypts as a final resting place for the bodies.

For the purpose mentioned, use is made of a chapel, provided with a floor opening adapted to be closed by an elevator platform for supporting a burial casket, the elevator extending in a receiving vault underneath the chapel, and wings extending outwardly from the chapel, each containing crypts arranged in tiers and adapted to receive burial caskets and bodies.

A practical embodiment of the invention is represented in the accompanying drawings forming a part of this specification, in which similar characters of reference indicate corresponding parts in all the views.

Figure 1 is a perspective view of the burial structure; Fig. 2 is a sectional side elevation of the same; Fig. 3 is a sectional plan view of the same; Fig. 4 is a transverse section of one of the crypt wings; and

Fig. 5 is a sectional elevation of the valves in the connections between adjacent crypt connections leading to a vertical ventilating crypt duct.

On a suitable foundation is erected a central or a tower structure A, preferably polygonal in sectional plan view, as plainly indicated in Fig. 3, and from the side walls of the central or tower structure A extend outwardly crypt wings B, each provided with tiers of crypts B' separated from each other by one longitudinal central partition B² and transverse partitions B³, so that each crypt B' has an entrance opening at the side wall of the wing B, each entrance opening being closed after the casket and body are stored in a crypt by a suitable door B⁴. The interior of each crypt B' is rendered moistureproof, preferably by a coating of asphaltum or other similar material.

The central or tower structure A is pro-

vided on the ground floor and between adjacent crypt wings B with doors C leading to a chapel D containing an altar E from which a minister or other person can conduct the burial service. In the middle of the floor of the chapel D is arranged an opening D' surrounded by a railing D² and leading to a receiving vault F underneath the chapel D and provided with racks G for temporarily storing bodies prior to the burial service and prior to placing the bodies in the crypts B'. The opening D' is adapted to be closed from underneath by an elevator platform H adapted to carry a bier and the casket containing the body over which the burial service is to be held at the time. The elevator platform H is mounted to slide up and down on suitable guideways H' arranged in the receiving vault F, and the elevator platform H is connected with chains H² extending upwardly and passing over pulleys H³, the terminals of the chains supporting counterbalancing weights H⁴ to normally hold the elevator platform H in an uppermost position so that the platform closes the opening D'. One end of a chain I is attached to the elevator platform H and extends under guide pulleys I' arranged on the floor of the receiving vault F, and the said chain I after passing over the last pulley I' extends upwardly through the floor of the chapel D and into the hollow altar E to wind up on a winding up mechanism I² mounted in the altar E.

Above the chapel D is arranged a fresh air receiving chamber J, provided in its side walls with screened air inlet registers J' for the admission of fresh air, and above the said chamber J is arranged a dome-shaped mixing chamber K connected in its bottom by a screened opening L with the top of the chamber J. A hinged door N serves to close the opening L whenever it is desired to do so. Into the mixing chamber K discharge main ventilating ducts O connected with the crypts B' and the receiving vault F to carry the gases or foul air from the crypts B' and the receiving vault F into the mixing chamber K to mix therein with the fresh air coming into the mixing chamber from the fresh air chamber J. The gases passing from the crypts B' and vault F into the mixing chamber K are lighter than the air, and hence the fresh air passing from the fresh air chamber J into

the mixing chamber K mixes intimately with the gases and the mixture gradually passes by way of the opening L into the chamber J and out of the same by the registers J' into the open air. The outer ends of the registers J' are provided with perforate covers J² to prevent ingress of air, dust, etc.

In the transverse partitions B³ of the crypt wings B are arranged vertically-disposed ventilating ducts P connected with the adjacent crypts B' by short pipes P' (see Figs. 2, 3 and 5), to keep the crypts B' ventilated. Each pipe P' is preferably provided with a valve Q, formed by baffle plates, and a hood (see Fig. 5), so as to permit air to pass from the crypt B' into the duct P, but to prevent return flow of air. The inner ends of the pipes P' are preferably provided with a perforate cover P², of woven wire or the like. The upper ends of the crypt ducts P open into horizontally-disposed copper pipes O' forming part of the main ducts O arranged on top of the uppermost crypts B' under the roofs of the wings B (see Figs. 2 and 4). Into the inner ends of the pipes O' open ducts R formed in the side walls of the chapel D and leading into the receiving vault F. The outer ends of the pipes O' terminate in pipes O² inclined upwardly and inwardly under the roofs of the wings B and leading to branch ducts O³ which open into the mixing chamber K. The lower ends of the crypt ducts P and the ducts R connect with air chambers S arranged under the bottom crypts B' and each chamber S is connected at the outer end by a short duct S' with the atmosphere so that fresh air can readily pass into the chambers S and receiving vault F and up through the ducts P and R so that the foul air is drawn out of the crypts B' and the receiving vault and passes by way of the members O', O² and O³ of the main ducts O into the mixing chamber K. The innermost crypts B', that is, those adjacent the chapel D, may have their doors B⁵ leading to the chapel D instead of to the outside.

From the foregoing it will be seen that a large intake of fresh air is provided underneath each wing B and the ducts are so arranged that a forced draft is produced to insure a proper ventilating of the crypts B' as well as the receiving vault F.

The walls of the burial structure may be made of reinforced concrete, but I do not limit myself to this particular material as stone, brick or other building materials may be employed.

Having thus described my invention, I claim as new and desire to secure by Letters Patent:

1. In a structure of the character described, a main compartment, a fresh air

receiving chamber above the said compartment and having registers in the side walls, a mixing chamber above the said receiving chamber and communicating with the same, main ventilating ducts opening into the said mixing chamber, a receiving compartment below the main compartment, the said main ventilating ducts communicating with the said receiving compartment, a plurality of compartments at the sides of the main compartment, and ventilating ducts in the walls of the side compartments, said ducts communicating with the interior of the compartments and leading to the said main ventilating ducts.

2. In a structure of the character described, a main compartment, a fresh air receiving chamber above the said compartment and provided in its peripheral side wall with registers, a mixing chamber above the said receiving chamber and communicating with the same, main ventilating ducts opening into the said mixing chamber, a receiving compartment below the main compartment, the said main ventilating ducts communicating with the said receiving compartment; a plurality of compartments at the sides of the main compartment, and ventilating ducts in the walls of the side compartments and having valved branch pipes communicating with the interior of the compartments, the said ducts leading to the top of the compartments to connect with the said main ventilating ducts.

3. In a structure of the character described, a main compartment, a fresh air receiving chamber above the said compartment and provided in its side wall with registers, a mixing chamber above the said receiving chamber and communicating with the same, main ventilating ducts opening into the said receiving chamber, a receiving compartment below the main compartment, the said main ventilating ducts opening into the said receiving compartment, a plurality of compartments at the sides of the main compartment, ventilating ducts in the walls of the side compartments and communicating with the interior of the compartments and leading to the top thereof to connect with the said main ventilating ducts, and fresh air supply chambers underneath the side compartments and into which open the ventilating ducts of the said side compartments.

4. In a structure of the character described, a main compartment, a fresh air receiving chamber above the said compartment, and provided in its side walls with registers, a mixing chamber above the said receiving chamber and communicating with the same, main ventilating ducts opening into the said receiving chamber, a plurality of compartments at the sides of the main compartment, and ventilating ducts pro-

vided with valved branch pipes communicating with the interior of the said side compartments.

5. In a structure of the character described, a main compartment, a fresh air receiving chamber above the said compartment and provided with registers, a mixing chamber above the said receiving chamber and communicating with the same, main 10 ventilating ducts opening into the said receiving chamber, a plurality of compartments at the sides of the main compartment, ventilating ducts in the walls of the side

compartments and communicating with the interior of the said side compartments and 15 the said main ventilating ducts, and valves in the connections between the walls of the side compartments and their ventilating ducts.

In testimony whereof I have signed my 20 name to this specification in the presence of two subscribing witnesses.

FRANK M. ROGERS.
